UNITED STATES PATENT OFFICE

MOSES CAPLAN, OF BOSTON, MASSACHUSETTS

DESIGN FOR A POCKET FOR POT HOLDER

Application filed January 20, 1933. Serial No. 46,906. Term of patent 7 years.

To all whom it may concern:

Be it known that I, MOSES CAPLAN, a citizen of the United States, and resident of Boston, county of Suffolk, and State of Massachusetts, have invented a new, original, and ornamental Design for Pocket for Pot Holder, shown in the accompanying drawing.

The figure is a front view showing my new,

original and ornamental design for pot holder.

I claim:

The ornamental design for a pocket for pot holder substantially as shown.

In testimony whereof, I have signed my name to this specification.

MOSES CAPLAN.
